CLAIM

(57) We claim the ornamental design for a reflective sign, as shown and described.

DESCRIPTION

FIG. 1 is a front elevation view of the reflective sign, in accordance with aspects of the present invention;

FIG. 2 is a rear elevation view thereof;

FIG. 3 is a right side elevation view of the reflective sign;

FIG. 4 is a bottom plan view of the reflective sign; and,

FIG. 5 shows a front elevation of a second embodiment of the reflective sign; all other elevation views are depicted in FIG. 2, FIG. 3, and FIG. 4.
